Lundgren, Paula R. et al., Design U.S. Appl. No. 29/556,771, filed Mar. 3, 2016 entitled "Tire Tread".

Primary Examiner — Robert M. Spear(74) *Attorney, Agent, or Firm* — Shaun J. Fox(57) **CLAIM**

The ornamental design for a tire, as shown and described.

DESCRIPTION

FIG. 1 is a side perspective view of a tire showing my new design, it being understood that the claimed pattern is repeated throughout the circumference of the tire, the opposite side being the same as that shown;

FIG. 2 is a front elevational view thereof, the opposite side being identical thereto;

FIG. 3 is an enlarged fragmentary front elevational view thereof; and,

FIG. 4 is a side elevational view thereof, the opposite side being the same as that shown.

In the drawings, the broken lines depict environmental subject matter only and form no part of the claimed design.
